(57) **CLAIM**

The ornamental design for table, as shown and described.

DESCRIPTION

FIG. 1 is a perspective view of a new design for a table; FIG. 2 is a side elevational view of the table shown in FIG. 1; the table is round and symmetrical and, therefore, all side elevational views are identical;

FIG. 3 is a top plan view of the table shown in FIG. 1; FIG. 4 is a top plan view of the table shown in FIG. 1 without the table top; and,

FIG. 5 is a bottom plan view of the table shown in FIG. 1. The broken lines in the drawings depict portions of the table that form no part of the claimed design.
